Primary Examiner — Robert M Spear*Assistant Examiner* — Ryan Harvey(74) *Attorney, Agent, or Firm* — Sand & Sebolt(57) **CLAIM**

The ornamental design for a trailer tank with wind deflector, as shown and described.

DESCRIPTION

FIG. 1 is a side elevational view of a trailer tank with wind deflector mounted thereon showing our new design.

FIG. 2 is an enlarged side elevational view of the trailer tank with wind deflector shown in FIG. 1.

FIG. 3 is a top plane view of FIG. 1.

FIG. 4 is a bottom plane view of FIG. 1.

FIG. 5 is an end elevational view of FIG. 1.

FIG. 6 is a top perspective view of FIG. 1.

FIG. 7 is a side elevational view of a trailer tank with wind deflector showing a second embodiment thereof;

FIG. 8 is a top plane view of FIG. 7.

FIG. 9 is a bottom plane view of FIG. 7.

FIG. 10 is an end elevational view of FIG. 7; and,

FIG. 11 is a top perspective view of FIG. 7.

The broken lines in the drawings represent unclaimed environmental subject matter and form no part of the claim.
